(57) **CLAIM**

I claim the ornamental design for a display screen with an animated graphical user interface, as shown and described.

DESCRIPTION

FIG. 1 is a first image in a sequence of a first embodiment for a display screen with an animated graphical user interface;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a first image in a sequence of a second embodiment for a display screen with an animated graphical user interface;

FIG. 9 is a second image thereof;

FIG. 10 is a third image thereof;

FIG. 11 is a forth image thereof; and,

FIG. 12 is a fifth image thereof.

The ornamental design which is claimed is shown in solid lines in the drawings. The broken line illustrates the display screen and forms no part of the claimed design. The broken lines illustrate portions of the animated graphical user interface and form no part of the claimed design.

The appearance of the transitional image sequentially transitions between the images shown in FIGS. 1-7 and 8-12. The process or period in which one image transitions to another image forms no part of the claimed design.
